MATCH BOOK

Reynolds Guyer, St. Paul, Minn., assignor to Wal-dorf Paper Products Company, St. Paul, Minn., a corporation of Minnesota

Application July 9, 1941, Serial No. 401,555

1 Claim. (Cl. 206—29)

My invention relates to match books and has for an object to provide a highly practical match book utilizing a block of matches constructed from a number of strips of paper slit longitudinally to provide stems having heads at their ends and stubs from which the stems issue.

Another object of the invention resides in providing a match book in which the matches are at all times permanently attached and in which the heads of the matches are at all times concealed.

A feature of the invention resides in providing a match book in which the matches may be removed and struck without opening the cover of the match book, whereby accidental lighting of the matches is prevented.

An object of the invention resides in providing a match book in which the stems are concealed prior to the use of the match book.

Another object of the invention resides in providing a match book including a cover constructed from a single strip of material having lateral edges and folded transversely of the edges to form a reverse sidewall, an obverse wall and an end portion intermediate the side walls.

An object of the invention resides in permanently and securely attaching the block of matches between the free ends of the side walls by means of a fastener or other device extending jointly through the same and in providing finger notches in the side walls through which access to the matches in the block may be had.

A feature of the invention resides in utilizing two notches, one in each side wall and in arranging the notches to extend inwardly from opposite lateral walls and toward the center so that access may be had to one-half of the matches through one notch and access had to the other one-half of the matches through the other notch.

An object of the invention resides in forming in the walls of the cover perforations defining detachable sections which protect the stems of the matches and which when removed from the notches by means of which access to the matches may be had.

Other objects of the invention reside in the novel combination and arrangement of parts and in the details of construction hereinafter illustrated and/or described.

In the drawing:

Fig. 1 is a perspective view of a match book illustrating an embodiment of my invention.

Fig. 2 is a view similar to Fig. 1 showing the

match book prior to removal of the sections from the cover.

Fig. 3 is a longitudinal sectional view of the match book shown in Fig. 1.

Fig. 4 is a developed view of the cover of the match book.

In the use of books of matches considerable danger occurs and damage is done through unintentional lighting of the entire block of matches due to accident and carelessness. This frequently occurs while the match is being struck to light the same. The present invention overcomes these disadvantages by providing a match book in which the heads of the matches while in the block are at all times protected and in which the cover does not have to be open to give access to the matches. In addition the stems of the matches are protected prior to use of the matches so that disengagement of the matches prior to removal of one of the detachable sections becomes impossible.

My invention is indicated in its entirety by the reference numeral A and comprises a block of matches B and a cover C therefor. These parts will now be described in detail.

A block of matches B may be of the ordinary conventional form and the matches disposed therein are indicated at 20. The block B consists of two sheets of paper 10 and 11 which are slit longitudinally to form a number of stems 13 issuing outwardly from stubs 14. The ends of the stems 13 are formed with heads 15 which are provided with the usual chemicals adapted to become ignited upon the striking on a proper striking surface. The block B is assembled by superimposing the two sheets 10 and 11 with the stubs 14 arranged one upon the other and securing the same together and to the cover, as will be subsequently more fully described. When the parts are so arranged, the heads 15 being of greater thickness than the stems 13, cause the block to become enlarged at the upper end, as is now the custom with ordinary books of matches.

The cover C of the invention is constructed from a blank 16, shown in Fig. 4, which is formed from a single strip of paper of suitable length having lateral edges 17 and 18. The blank 16 is formed with two spaced scores 19 and 21 intermediate the ends which divide the blank into an obverse wall 22, a reverse wall 23 and an end portion 24 therebetween. When the blank is folded along the scores 19 and 21, the two side walls 22 and 23 are brought into overlying position and a space 25 provided therebetween in which the block of matches B is inserted. The

blank is of such a length that the edges 26 and 27 of the side walls 22 and 23 lie flush with the ends of the stubs 14 of the block B. The block B is permanently and securely attached between the two side walls 22 and 23 with the heads 15 of the matches opposite the end portion 24 by means of a wire stitch or staple 28 which passes jointly through said walls and the stubs 14. In this manner the block of matches is contained entirely within the space 25 and the heads completely concealed and protected by the end portion 24.

In the obverse side wall 22 are formed perforations 35 which weaken the said wall and provide a section 36 which is readily removable from the wall by tearing the wall along said perforations. When the said section is removed a finger notch 31 is formed in the wall 22 which notch extends inwardly from the lateral edge 18 of the blank 16 and to a position in close proximity to the center of the blank. This finger notch is situated intermediate the score 19 and the edge 26 of the blank to leave a protecting portion 32 on the wall 22 which covers the heads 15 of the matches. In the reverse wall 23 are similarly formed perforations 37 which provide a removable section 38 in said wall. When this section is removed a finger notch 33 is formed in said wall which extends through the edge 17 of the blank 16 and inwardly toward the center of the blank. This notch is also disposed in spaced relation to the score 21 and to provide a protecting portion 34 on the blank, similar to the protecting portion 32. By means of the notches 31 and 33 access may be had to the stems 13 of the matches 20 intermediate the heads 15 and the stubs 14. The outermost of the matches 20 can thus be removed one at a time by extending the finger into the said notches and breaking the stems away at the stubs 14. It will readily be comprehended that one-half of the matches 20 are accessible through the finger notch 31 and the other one-half are accessible through the finger notch 33.

Upon the outer surface of the blank 16 and adjacent the edges 26 and 27 of the walls 22 and 23 are provided suitable coatings 39 which form striking surfaces on which the matches to be lighted may be struck.

It will be noted that the block of matches B are disposed inwardly of the lateral edges of the walls 22 and 23. This gives ready access to the marginal portions of the sections 22 and 23 so as to facilitate removal of said sections.

The use of the invention is apparent. When the matches are packaged the sections 36 and 38 are left attached to the walls 22 and 23 so that the stems of the matches are protected. Only when it becomes desirable to use the matches

is one of the sections 36 or 38 removed. Upon removal one half of the matches become accessible through the finger notch formed by its removal and the matches so exposed can be removed one at the time. When one half the matches have been used the other detachable section is removed and the rest of the matches become accessible.

The advantages of my invention are manifest. 10 An extremely simple and practical construction is provided whereby blocks of matches may be conveniently carried about. The matches, being permanently and rigidly secured between the side walls of the cover, the same are at all times 15 protected. The user does not have to fumble in opening the cover as the matches are immediately available through the finger notches.

By the use of the removable sections for forming the finger notches, the stems are protected 20 until the matches are required for use. Thus the matches are completely concealed until desired for use, reducing the danger which might be occasioned by children playing with the unopened match books. The sections while attached to the cover stiffen and strengthen the same.

Changes in the specific form of my invention, as herein disclosed, may be made within the scope of what is claimed without departing from the spirit of my invention.

Having described my invention, what I claim as new and desired to protect by Letters Patent is:

A match book comprising a cover constructed from a single strip of material having lateral edges and folded transversely of said edges to form a reverse side wall, an obverse side wall and an end portion intermediate the side walls, a block of matches constructed from a plurality of overlying sheets of paper slit longitudinally to provide a number of stems having heads at their 35 ends and stubs from which the stems issue, said block of matches being disposed between the side walls of the cover with the heads adjacent the end portion and the stubs between the ends of the side walls, said obverse side wall having a removable area in the same extending from one of the lateral edges thereof and inwardly toward the center of said side wall, and defined by the continuous weakened line of separation, said removable area exposing when removed a portion 40 of the matches, said reverse side wall having a second removable area extending from the lateral edge thereof opposite the other lateral edge of the obverse side wall, and inwardly toward the center of said reverse side wall, and exposing when removed the remainder of the matches, and means for rigidly securing the stubs to both 45 of the side walls.

REYNOLDS GUYER.
